CUTTER CHAIN FOR MINING MACHINES

Oswald Floyd Lewis, near Sheffield, England, assignor of one-half to Newton, Chambers & Company Limited, near Sheffield, England, a corporation of Great Britain

Application December 23, 1939, Serial No. 310,848
In Great Britain December 23, 1938

9 Claims. (Cl. 262—33)

This invention relates to cutter chains for mining machines, and the invention is concerned particularly with a cutter chain having its picks or cutters projecting from one side of the chain for use on a machine for cutting out a core of coal or other mineral by means of the side-cutting chain running on an open rectangular jib which is moved transversely through the mineral to be mined.

In such cases it is desirable that the pitch between any two adjacent pivot pins joining the pick boxes and connecting links into an endless chain should be kept as small as possible and that the pick boxes themselves should be short and compact as these conditions facilitate the guiding and driving of the chain since they increase its flexibility and they also make it possible to run the chain round sharp curves at the corners of the jib frame.

Accordingly one object of the present invention is to provide a cutter chain having the component pick boxes of compact construction with the pitch between the pivot pins mounted therein reduced as far as practically possible and another object is to enable the chain to be constructed in an expeditious manner and at low cost.

A cutter chain according to the invention has the pick boxes thereof each constructed with a pick block welded to a structure built up from a pair of opposing flat members spaced apart but connected together by a central connecting member having its ends fitted into holes located centrally between the ends of the flat members and welded into place in those holes. In the case of a side-cutting chain the pick block, in which a cutting pick or a pair of picks is or are secured in the usual manner, is welded to the outside face of one of the flat members and the pivot pins on which the connecting links hinge are inserted through the opposite member and have projecting ends extending into recesses in the pick block and are secured therein by locking pins or wires. The central connecting member is preferably tubular and has opposite parts of its wall curved inwardly to clear the curved ends of the links.

The accompanying drawings illustrate, by way of example, a construction of side cutting chain according to the invention. In the drawings—

Fig. 1 is a plan view of a portion of the chain, partly in section taken along line 1—1 of Fig. 2.

Fig. 2 is a rear view of the chain, i. e., looking at the face which contacts with the bottom of the channel guide in which the chain runs on the jib.

Fig. 3 is an end view of one of the pick boxes of the chain with the picks omitted, and

Fig. 4 is a sectional view taken on line IV—IV of Fig. 1.

5 The chain is intended to run in a guide channel in an upright open frame or jib which is generally of rectangular shape and has the cutters or picks of the chain projecting from the guide channel on one side of it so that a core 10 of coal or other mineral can be cut out by giving the jib an advancing movement at right angles to its plane in the direction in which the picks project. In the following detailed description the part of the chain from which the pick blocks 15 and picks project (which is actually a side face of the chain relative to the directions in which the chain is flexible) will consequently be referred to as the front of the chain while the face of the chain which bears on the bottom of the 20 channel in which the chain is guided will be referred to as the rear of the chain.

Each pick box is built up of several main parts welded together, namely a rear member 1, a front member 2, a connecting member or tube 3 joining the front and rear members, and a pick block 4 projecting from the front face of the front member 2. The rear member 1 consists of an oval shaped plate or forging having projecting from its front face adjacent its straight 25 edges a pair of ribs or flanges 5 for engagement with retainers or shoulders projecting from the sides of the guide channel in the jib to keep the chain properly in the guide channel, and the front member 2 is also of oval shape and similarly provided with flanges 6 for engagement 30 with the other edges of the retaining shoulders provided in the chain guide channel, but the front face of the member 2 is enlarged to form a flange or cover 7 which extends over the edges 35 of the jib guide when the chain is in place therein so that the cover 7 assists in preventing the entry of chips or dust from the picks into the 40 guide channel.

Each of the members 1 and 2 is provided with 45 a central hole shaped to fit one end of the connecting member 3 joining the front and rear members and the connecting member is here shown as a tube having two opposite flat parallel wall portions 3a joined by inwardly curved wall portions 3b, as will be clear from Fig. 2. The members 1 and 2 are welded to the connecting member 3 by welds 8 at the ends of the tube 50 constituting the connecting member. The rear end of the connecting tube 3 is closed or partly 55

closed by a suitably shaped piece of flat plate 9 secured in the end of the tube by welds 10.

To the front face 2a of the front member 2 is welded the pick block 4 provided with the usual sockets 11 for the picks 12 which are secured in place by holding bolts 13. The fact that the connecting member 3 is a tube enables the blunt ends of the picks to project right through the pick block 4 and into the interior of the connecting member if necessary, and for the same reason the front end of the tube 3 is not brought right through to the front of the member 2 but stops short as shown. The welding by which the pick block 4 is secured to the member 2 is indicated at 44. Although the pick blocks illustrated are constructed to take two picks, other pick blocks provided with single pick sockets or with pairs of sockets at other angles to those shown may be used instead, and as the pick blocks are merely welded to the front faces 2a of the front members 2 it is easily possible to construct a pick box to take any desired arrangement of picks by welding on a suitable pick block.

The pick boxes are joined together to form an endless chain by the provision of connecting links 14 which are coupled to the pick boxes by pivot pins 15 (Fig. 1) on which the links can turn as the chain flexes. As the back face 1a of the rear member 1 has to slide along the bottom of the chain guide channel the pivot pins 15 are recessed into the member 1 and consequently each pin has a countersunk head 16 which fits into a countersunk hole 17 in the rear member 1 while the remainder of the pin extends through a hole in the adjacent link and projects through a fitted hole 18 in the front member 2. The pivot hole in the link has a wearing liner 19 (Fig. 1) with a channel 20 for lubricant therein. The lubricant such as oil, is supplied to the channel 20 by an oil passage 21 drilled in the pin, the outer end of the longitudinal portion of the passage 21 being closed by a screwed plug 22 although oiling can still be effected through the transverse oil hole 23 in the projecting end 24 of the pivot pin 15.

In order to provide a compact construction and to facilitate the guiding and driving of the chain the two pivot pins 15 of each pick box have their projecting ends 24 recessed into the side faces of the pick block 4 which is therefore cut away as indicated at 25 to clear the projecting ends 24 which are correspondingly stepped as indicated at 26.

Each pin is held in place by a short rod or wire 27 which is fitted into opposed grooves in the pin and block which may be formed by a hole drilled partly through the pin and partly through the side of the recess 25 in the pick block as shown by the section in Fig. 1, and the ends of the wires 27 are turned over as shown at 28 to prevent the wire from working out. To facilitate the insertion or removal of the wires 27 the head 16 of each pivot pin is provided with a slot 29 for a screwdriver by which the pin can be turned to bring the two parts of the hole for the wire into proper alignment.

Each of the links 14 has flanges 30 for co-operation with the retaining shoulders in the guide channel, similarly to the flanges 5 and 6 of the members 1 and 2. The driving of the chain takes place through the teeth of a driving sprocket engaging in suitably shaped holes 31 in the links 14.

The above described construction enables pick

boxes to be built up very quickly and at a low cost since the component parts are easily made and fitted together and can be quickly welded together to produce a complete pick box and the finished pick boxes can be rapidly assembled with the links to form a complete chain by the insertion and securing of the pivot pins by simple operations.

The completed pick boxes are compact and have the pitch between the pivot pins reduced by the recessing of the projecting ends of the pins into the pick blocks when the pick boxes are constructed for side cutting chains.

What I claim as my invention and desire to secure by Letters Patent is:

1. In a mining machine cutter chain, a pick box structure comprising opposing spaced flat members, said members having centrally disposed holes formed therein between the ends thereof, a tubular member extending transversely between said spaced flat members with its ends fitted into said holes and welded therein, and a pick block welded to said structure.

2. In a mining machine cutter chain, a pick box structure comprising opposing spaced flat members, said members having centrally disposed holes formed therein between the ends thereof, a tubular member extending transversely between said spaced flat members with its ends fitted into said holes and welded therein, and a pick block welded to the outer face of one of said flat members.

3. In a mining machine cutter chain, a pick box structure comprising opposing spaced flat members receiving between them the rounded ends of connecting links, said members being connected by a tubular member having opposite flat wall portions joined by concave wall portions of the same curvature as the rounded ends of the links, the ends of said tubular member fitting into appropriately shaped holes midway between the ends of said flat members and being welded therein.

4. In a mining machine cutter chain, a pick box structure, comprising opposing spaced flat members, a connecting member connecting said flat members together, said connecting member including an end recess extending between central portions of said flat members and being inwardly spaced from the ends of said flat members, and a pick block integrally connected to an outer flat side of one of said flat members, said pick block including removable picks and the inner ends of said picks being receivable in said end recess of said connecting member.

5. In a mining machine cutter chain, a pick box structure, comprising opposing spaced flat members, a connecting member connecting said flat members together, said connecting member extending between central portions of said flat members and being inwardly spaced from the ends of said flat members, a pick block integrally connected to one of said flat members, said flat members having centrally disposed opposing holes formed therein, said connecting member being received in said holes, means integrally connecting said connecting member to said flat members and said connecting member comprising a tube open at least at one end.

6. In a mining machine cutter chain, a pick box having front and rear faces, a pick block secured to said front face, said block having end faces, links at each end of said box adapted to connect said box to adjoining boxes, pivot pins pivotally connecting said links to said box, one

end of each of said pins extending outwardly of the front face of said box adjacent an end face of said block, locking means for retaining said pins in place, said locking means being insertable between said projecting end of each of said pins and the adjacent end face of said block.

7. The structure of claim 6, opposable grooves in said projecting ends of said pins and said end faces of said block, and said locking means comprising locking pins receivable in said grooves.

8. The structure of claim 6, recesses in said end faces of said block partially receiving said projecting ends of said pins, opposable transverse grooves in said projecting ends of said pins

and the floors of said recesses, and said locking means comprising locking pins receivable in said grooves.

9. In a mining machine cutter chain, a pick box structure, comprising spaced and opposed flat members, a hollow member connecting said flat members together centrally thereof, a pick block integrally connected to an outer flat side of one of said flat members, an opening through said last flat member into the interior of said connecting member, and pick receiving openings through said pick block and opening into said opening of said last named flat member.

OSWALD FLOYD LEWIS.
